CLAIM

The ornamental design for a light barrier element of a guillotine-type cutting machine, as shown and described.

DESCRIPTION

FIG. 1 is a perspective view of a light barrier element of a guillotine-type cutting machine taken from a light barrier side of the light barrier element, showing a cover element thereof in a covered position;

FIG. 2 is a perspective view of the light barrier element of a guillotine-type cutting machine taken from a side opposite the light barrier side of the light barrier element of a guillotine-type cutting machine, showing the cover element in the covered position;

FIG. 3 is a top perspective view of the light barrier element of a guillotine-type cutting machine, showing the cover element in the covered position;

FIG. 4 is a perspective view of the light barrier element of a guillotine-type cutting machine taken from the side opposite the light barrier side of the light barrier element of a guillotine-type cutting machine, showing the cover element in the uncovered position; and,

FIG. 5 is a top perspective view of the light barrier element of a guillotine-type cutting machine, showing the cover element in the uncovered position.

The broken lines, encompassing unshaded regions, represent the bounds of the claimed design while all other broken lines are directed to environment and are for illustrative purposes only; the broken lines form no part of the claimed design.
